SUPPORT FOR CONCRETE REINFORCING STEEL

Edward E. Welch, Sacramento, Calif.

Application October 3, 1932. Serial No. 636,064

1 Claim. (Cl. 72—122)

This invention appertains to new and useful improvements in reinforced concrete work and more particularly to a support for reinforcing elements.

5 The principal object of the present invention is to provide a support for concrete reinforcing steel wherein a base is employed which will only have a small area of its surface in contact with the form so that when the form is removed 10 practically none of the support is bare.

Another important object of the invention is to provide a support for concrete reinforcing steel wherein the support is of curved construction so that even in the event the same tilts in 15 the form, only a small area of its surface will be in contact with the form.

Other important objects and advantages of the invention will become apparent to the reader of the following specification.

20 In the drawings:—

Figure 1 represents a top plan view of one style of support base.

Fig. 2 represents a side elevational view of the structure shown in Fig. 1.

25 Fig. 3 represents a top plan view of another support base structure of substantially larger proportions.

Fig. 4 represents a side elevational view of the structure shown in Fig. 3.

30 Fig. 5 represents a top plan view of the base with the tie wires upstanding.

Fig. 6 represents a side elevational view of the structure shown in Fig. 5, this form of the invention being without the convoluted internal 35 reinforcing means.

Fig. 7 represents a perspective view of the support in use supporting a bottom steel.

Fig. 8 represents a perspective view of the support upon which is mounted a high chair or 40 an elevated steel.

Fig. 9 represents a vertical sectional view through the base shown in Fig. 8, showing the manner in which the tie elements are disposed prior to application of the steel or high chair 45 thereto.

Referring to the drawings wherein like numerals designate like parts, it can be seen in Figs. 1 and 2, that the support consists of a hemispherical shaped base 5 having a flat top surface 6 diametrically across which is a groove 7. The 50 form of the invention shown in Figs. 3 and 4 is substantially identical with the forms shown in Figs. 1 and 2 excepting that the groove 7' shown in Fig. 4 is of less depth than the groove 7 and

is for use where the concrete layer is of a greater depth.

In both of these forms 5 and 5', a coiled reinforcing element 8 is embedded in the base when the convolutions pull apart in the manner substantially shown in dotted lines in Figs. 1 and 3.

Embedded in the bases 5 and 5' are the U-shaped tie elements 9—9, each being of ductile material having its bight portion embedded in the base 5 in the manner substantially shown in Fig. 9. It will be observed, that the bight portion of each of these elements is twisted to provide an offset 10 which obviously prevents pulling through or slipping through of the tie element from the base 5 or 5'.

In conjunction with either the base 5 or base 5', a high chair such as is disclosed generally by numeral 11 in Fig. 8 can be employed. This high chair consists of inverted U-shaped bar 12 having its leg portions offset horizontally with 75 respect to each other in a lateral direction with each leg provided with a foot portion 13, the feet being of parallel spaced relation as shown in Fig. 8 and resting upon the top surface 6 of the base 5 bridging the aforementioned channel or groove 7.

As is clearly shown in Fig. 8, the elevated steel 14 is tied as at 15 to the elevated bight portion 16 of the high chair 12 while the feet 13 are secured to the top surface 6 of the base 5 by 85 adjacent ends of the tie elements 9 being disposed thereover and twisted as at 17.

Thus the high chair is secured to the base 5 and while it is the tendency of the base 5 to maintain a position with its surface 6 substantially horizontal, if there is any likelihood of the base 5 tilting in the form, the form being denoted by numeral 18, no increased surface area of the base will contact with the form due to the hemi-spherical shape of the base. With such a base construction, only a very slight surface area of the curved portion of the base will be exposed through the concrete after the form is removed. Thus the form will be almost entirely embedded in the concrete, thus increasing its 90 efficiency and its ability to withstand greater strain without displacement from the concrete.

Fig. 7, shows the base 5 or 5' with a bottom steel 19 disposed in the groove 7 thereof and with the tie element 9 trained thereover and 105 twisted as at 20 to secure the steel to the base and in resting position within the groove 7.

While the foregoing specification sets forth the invention in specific terms, it is to be understood that numerous changes in the shape, size 110

and materials may be resorted to without departing from the spirit and scope of the invention as claimed hereinafter.

Having thus described my invention, what I claim as new is:—

A support for spacing concrete reenforcing steel from concrete forms, comprising a hemi-

spherical shaped body having its curved surface for contact with a concrete form and means on the body whereby the said body can be secured to a concrete reenforcing steel so that the reenforcing steel will lie diametrically across the flat side of the body.
